TUNABLE COUPLING CIRCUIT ARRANGE-
MENT FOR ULTRA-SHORT WAVESKurt Schlesinger, Berlin, Germany, assignor, by
mesne assignments, to Loewe Radio, Inc., a cor-
poration of New YorkApplication February 19, 1938, Serial No. 191,450
In Germany February 24, 1937

6 Claims. (Cl. 179—171)

If a large tuning range of the received signals and at the same time wide-band amplification is required of an ultra-short wave receiver, difficulties are encountered when employing the normal oscillatory circuit arrangements. The unavoidable inter-electrode capacities and the inherent earth capacities call in the case of a given wave range for a comparatively large capacity of the rotating plate condenser. These two in parallel lead to a very small coil in the case of a given wavelength. This results in a large

$$\frac{C}{L}$$

in a small oscillation resistance. It is accordingly necessary to perform strong damping, and poor amplification is obtained. In order to reduce this detrimental effect the applicant has already proposed previously to reduce the working capacity by a series connection of the tuning condenser C_a with the inherent capacity C_i of a preceding tube. The working capacity is then always smaller than C_i . The coil L is accordingly considerably larger. The following example serves for explanation:

C_a rotating plate condenser with a range of 5—25 cm.

$$C_i=10 \text{ cm.}$$

In case of parallel connection the maximum capacity amounts to

$$C_{\max}=35 \text{ cm.}, \text{ and the minimum capacity}$$

$$C_{\min}=15 \text{ cm.}$$

$$\frac{\lambda_{\max}}{\lambda_{\min}}=\sqrt{2.3}=1.5$$

The tuning range of the circuit arrangement is accordingly very small.

In the case of series connection the detrimental working capacity is much smaller, as

$$C_{\min}=3.2 \text{ cm.}$$

$$C_{\max}=7 \text{ cm.}$$

The tuning range, therefore, is

$$\sqrt{2.2}$$

i. e. is equally as small. For a given wave length, however, the coil is five times as large. The os-
cillation resistance equals

$$\sqrt{\frac{L}{C}}$$

in the series connection is accordingly also five times as large as in the parallel connection.

There is accordingly obtained in the series connection with a given width of band an amplification which is five times as great, as it is possible to employ one-fifth of the damping.

There will be recognised from the examples given the obvious fundamental superiority of the series connection of C_i and C_a as compared with the parallel connection. At the same time, however, it will also be recognised that the receiving range, i. e. the ratio

$$\frac{\lambda_{\max}}{\lambda_{\min}}$$

is equally poor in both cases. Moreover the series connection has at the same time the particular disadvantage that the tuning curve varies only in lagging fashion with the angle of rotation towards the longer waves.

The invention will be clearly understood by way of examples shown in the accompanying drawing, wherein

Figs. 1, 2 and 3 show the fundamental two circuit arrangement of parallel connection (Fig. 1) and series (Figs. 2 and 3) already above dealt with.

Figs. 4—5 show exemplary embodiments of the present invention.

The circuit system as shown in Fig. 3 avoids the disadvantage above mentioned whilst the amplification advantages of the series connection are maintained. In this circuit system there are employed two rotating plate condensers C_{a1} and C_{a2} , which are coupled together and are varied in the same sense. C_{a1} is parallel to C_i . The condenser C_t is a trimmer. The condenser C_{a1} is in parallel with the inherent tube capacity C_i , and these two capacities together are in series with the tuning condenser C_{a2} . If both tuning condensers C_a have a range of 5—25 cm. capacity and if C_i is again 10, the effective capacity parallel to the coil amounts to 3.5—15 cm. corresponding to a ratio of the receiving range of

$$\sqrt{4}=2$$

The maximum capacity in the case of the longest wave amounts to merely 15 as compared with 35 in the usual circuit system according to Fig. 1. The oscillation resistance, therefore, although not so good, is still more than twice as great as in Fig. 1.

With tuning condensers of 50 cm. tuning ranges are obtained of approximately 1:2.6, i. e. a very useful value. The tuning curve of the circuit system with double condenser according to the invention already closely approaches to a straight line in the case of circular plate condensers.

The flattening towards the longer tuning waves, which represents an appreciable disadvantage in the simple series connection according to Fig. 2, is in this case eliminated.

5 The damping of the tuning circuit formed by L and C_{a1} , C_{a2} takes place by a damping resistance R parallel to the coil. The feeding of the grid or anode circuits with the bias can be advantageously effected at the centre of the coil

10 10 L via the choke D_1 . This point is effectively at earth potential for the high frequencies.

The trimming of the circuit system is particularly simple. There is provided merely one trimmer C_t for tuning the inherent tube capacities.

15 15 In the case of predetermined values for C_a and L, which are always the same, there is then obtained an ideal unison of several circuits by increasing by means of C_t the too small associated inherent capacities C_i to the greatest value occurring in the circuit system. The frequency curves then exactly coincide. In particular it is then possible to unite two circuits of this kind to form a band filter.

20 20 In Fig. 4 there is shown as an embodiment of the present invention a band filter circuit of this character employed as intermediate coupling between two tubes V_1 and V_2 . In this case, generally speaking, the damping resistances R parallel to the coils L can be omitted, since a coupling 25 resonance effect may be produced thus effecting a natural widening of the receiving frequency curve. In the anode circuit of valve V_1 , coil L_1 , tuning condensers C_{a1} and C_{a2} are connected in series and all this series connection in parallel 30 to the anode-cathode path of valve V_1 . The capacity C_{ta} (so called trimmer) connected in parallel to condenser C_{a2} is used for adjusting unison. In similar manner the grid circuit of the associated valve V_2 is connected. L_2 is the coupling 35 coil connected in series with the tuning condensers C_{g1} and C_{g2} and this whole series connection is in parallel to the grid-cathode path of valve V_2 . By the capacity C_{tg} which is connected in parallel to C_{g2} the unison of the circuit is adjusted.

40 40 In Fig. 5 there is set forth a special structural embodiment of the tuning condenser C_a in combination with a trimmer C_t . As will be recognised from Figs. 3 and 4, the two rotors of the two condensers C_{a1} and C_{a2} may be electrically connected together in the circuit according to the invention. It is accordingly possible to place at least the two condenser halves of a circuit and also even compound condensers of coupled circuits on a common metallic shaft O, as shown in Fig. 5. According to the invention there may be fitted on this shaft metallic intermediate discs S_1 , S_2 and S_3 connected with the shaft. R_{a1} , R_{a2} and R_{g1} , R_{g2} are the rotor plates of the single tuning capacities C_{a1} , C_{a2} and C_{g1} and C_{g2} (shown in Fig. 4). The discs S_1 and S_3 separate the two stator halves of the two single circuits. The stray capacity parallel to the coil is thus divided in each case into two capacities to earth, i. e. parallel to the tuning parts. If the screening discs S_1 and S_3 in particular are made to be shiftable on the shaft, as indicated by an arrow in Fig. 5, the capacity C_t shown in broken lines between the stator assembly on the anode side and 55 this disc acts simultaneously as trimmer. In place thereof there may, of course, also be employed a separate small condenser C_t , which is connected with one electrode to earth and in consequence can be readily adjusted without detuning the circuit system as shown in Fig. 5 in

60 combination with the grid circuit of valve V_2 . The other electrode is joined up with the stator half of the compound condenser connected to the tube. In Fig. 5 there is included the band filter connection according to Fig. 4 in order to illustrate the connection with the special condenser arrangement. Coils and condenser assemblies after being connected together can preferably be introduced into an earthed screening casing 10.

65 The requirement frequently arises for coupling the tuning circuits according to the invention with a local oscillator, which in the case of super-heterodyne receivers should then traverse in constant frequency spacing the same receiving range with a tuning curve as analogous as possible. It has been found, and will also be readily recognised, that the circuit system according to the invention does not essentially require to be employed for a local oscillator of this character, and that it is possible to use for this oscillator the usual parallel connection of C and L or other known circuit systems. The reasons leading up to the circuit system according to the invention relate purely to amplification, and fundamentally cease to exist in respect to a local oscillator. According, therefore, to the invention, a local oscillator having rotating plate condensers with the same form of plate, but with parallel connection of C and L and correspondingly greater

$\frac{C}{L}$

70 can be mechanically coupled with advantage with amplifying circuits and band filter systems of the compound condenser connections according to the invention as shown in Figs. 4 to 5. The tuning curves are completely identical in their form if the plate section is the same. The trimming of the local oscillator to the correct receiving range is a problem which has become a matter of course in the present-day radio art.

I claim:

1. In an amplifier arrangement two tunable coupling circuits for coupling two successive amplifier stages for effecting wide-band amplification, more particularly for ultra-short wave circuits, each of said coupling circuits consisting of a valve, a coil and a tunable capacity, said tunable capacity being divided into two single condensers which are varied synchronously and connected in series with said coil, one of said condensers being connected in parallel to the valve and having connected in parallel a special condenser of adjustable capacity with respect to earth, said coils being inductively coupled with each other in such manner that a wide-band is amplified, said first tunable circuit being connected in parallel to one of said stages, said second tunable circuit being connected in parallel to the grid-cathode path of the associated valve.

2. In an amplifier arrangement two tunable coupling circuits for coupling two successive amplifier stages for effecting wide band amplification, more particularly for ultra-short wave circuits, each of said coupling circuits consisting of a valve, a coil and a tunable capacity, said tunable capacity being divided into two single condensers which are varied synchronously and connected in series with said coil, one of said condensers being connected in parallel to the valve and having connected in parallel a special condenser of adjustable capacity with respect to earth, said coils being inductively coupled with each other in such manner that a wide-band is

- amplified, said first tunable circuit being connected in parallel to one of said stages, said second tunable circuit being connected in parallel to the grid-cathode path of the associated valve, the rotors of said tunable condensers being mounted on a common earthed shaft, the stators being disposed in axial direction in relation to each other and screened one from another by an intermediate earthed sheet.
10. 3. In an amplifier arrangement two tunable coupling circuits for coupling two successive amplifier stages for effecting wide-band amplification, more particularly for ultra-short wave circuits, each of said coupling circuits consisting of a valve, a coil and a tunable capacity, said tunable capacity being divided into two single condensers which are varied simultaneously and connected in series with said coil, one of said condensers being connected in parallel to the valve, said coils being inductively coupled with each other in such manner that a wide-band is amplified, said first tunable circuit being connected in parallel to one of said stages, said second tunable circuit being connected in parallel to the grid-cathode path of the associated valve, the rotors of said tunable condensers being mounted on a common earthed shaft, the stators being disposed in axial direction in relation to each other and screened one from another by an intermediate earthed sheet, said intermediate sheet being axially shiftable for the purpose of tuning additionally the inherent capacity of the circuit arrangement.
4. In an amplifier arrangement two tunable coupling circuits for coupling two successive amplifier stages for effecting wide-band amplification, more particularly for ultra-short wave circuits, each of said coupling circuits consisting of a valve, a coil and a tunable capacity, said tunable capacity being divided into two single condensers which are varied synchronously and connected in series with said coil, one of said condensers being connected in parallel to the valve and having connected in parallel a special condenser of adjustable capacity with respect to earth, said coils being inductively coupled with each other in such manner that a wide-band is amplified, said first tunable circuit being connected in parallel to one of said stages, said second tunable circuit being connected in parallel to the grid-cathode path of the associated valve, the rotors of said tunable condensers being mounted on a common earthed shaft, the stators being disposed in axial direction in relation to each other and screened one from another by an intermediate earthed sheet, said intermediate sheet being axially shiftable for the purpose of tuning additionally the inherent capacity of the circuit arrangement, both said coupling circuits being enclosed by an earthed screening casing.
5. In an amplifier arrangement two tunable coupling circuits for coupling two successive amplifier stages for effecting wide-band amplification, more particularly for ultra-short wave circuits, each of said coupling circuits consisting of a valve, a coil and a tunable capacity, said tunable capacity being divided into two single condensers which are varied synchronously and connected in series with said coil, one of said condensers being connected in parallel to the valve and having connected in parallel a special condenser of adjustable capacity with respect to earth, said coils being inductively coupled with each other in such manner that a wide-band is amplified, said first tunable circuit being connected in parallel to one of said stages, said second tunable circuit being connected in parallel to the grid-cathode path of the associated valve, both said coupling circuits being enclosed by an earthed screening casing.
6. In an amplifier arrangement two tunable coupling circuits for coupling two successive amplifier stages for effecting wide-band amplification, more particularly for ultra-short wave circuits, each of said coupling circuits consisting of a valve, a coil and a tunable capacity, said tunable capacity being divided into two single condensers which are varied synchronously and connected in series with said coil, one of said condensers being connected in parallel to the valve, said coils being inductively coupled with each other in such manner that a wide-band is amplified, said first tunable circuit being connected in parallel to one of said stages, said second tunable circuit being connected in parallel to the grid-cathode path of the associated valve, the rotors of said tunable condensers being mounted on a common earthed shaft, the stators being disposed in axial direction in relation to each other and screened one from another by an intermediate earthed sheet, said intermediate sheet being axially shiftable for the purpose of tuning additionally the inherent capacity of the circuit arrangement, both said coupling circuits being enclosed by an earthed screening casing.

KURT SCHLESINGER.
